Primary Examiner — Wan Laymon(74) *Attorney, Agent, or Firm* — Revolution IP, PLLC(57) **CLAIM**

The ornamental design for an apparatus for lower limb rehabilitation, as shown and described.

DESCRIPTION

FIG. 1 is a top, front right perspective view of an apparatus for lower limb rehabilitation showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, rear right perspective view thereof;

FIG. 9 is a bottom, front right perspective view thereof; and,

FIG. 10 is a reference view showing use state thereof.

The broken lines in FIGS. 7, 9 and 10 are included for the purpose of illustrating portions and environmental element of the apparatus for lower limb rehabilitation and form no part of the claimed design.
